UNITED STATES PATENT OFFICE

FEDERICO GUILLERMO DIAGO, OF HABANA, CUBA

STOCK AND CASH KEEPER

Application filed August 29, 1925. Serial No. 53,313.

This invention relates to improvements in registering apparatus, and it consists in the constructions, combinations and arrangements herein described and claimed.

5 An object of the invention is to provide a device by means of which a storekeeper, for example, may easily keep account of his stock in trade and the amount of cash received from the sale of articles from the 10 stock, thereby eliminating the customary laborious bookkeeping and writing.

Another object of the invention is to provide a combined device by means of which can be registered the sales of stock in trade 15 and the money received as a result of such sales.

Other objects and advantages appear in the following specification, reference being had to the accompanying drawings, in 20 which

Figure 1 is a perspective view of the improved stock and cash keeper.

Figure 2 is a detail sectional view of the base alone illustrating the rocking function 25 of the cash-drawer.

Figure 3 is a detail perspective view of the cash drawer.

Figure 4 is a perspective view of the base sections, illustrating the registering apparatus referred to below.

Figure 5 is a detail perspective view of one of the registering units.

Figure 6 is a plan view of another registering unit.

35 In carrying out the invention provision is made of a base 1 consisting of relatively stationary and movable sections 2 and 3. The movement of the section 3 is that of a rocker, and the movement occurs in relation to the 40 section 2 to which the rocker section 3 is pivoted as at 4 (Fig. 2).

The rocking movement of the section 3 is accompanied by the sliding out of the cash drawer 5. Although this drawer is equipped 45 with a knob 6 it is intended to slide out of its own accord when the section 3 is tilted as shown in dotted lines in Figure 2. The drawer has a lock 7 for the sake of security when the device is not in use.

50 A plurality of partitions 8 divide the cash

drawer into a number of compartments which are employed for various coins and bills. Stops 9 (Figs. 2 and 3) limit the outward movement of the cash drawer. Strips of rubber 10 or other suitable material along 55 the lower edge of the drawer ride upon the guides 11 and have the tendency of supplying friction in such amount that the drawer will not slide out too rapidly. The rubber or other strips also assist in preventing any sound which might accompany the motion 60 of the drawer.

It is intended that the device shall furnish a continuous visible account of the amount 65 of stock remaining on hand. To this end the section 2 has as many registering units 12 (Figs. 4 and 5) as there are articles of different kinds in stock. The description of one will suffice for all.

A hand plate 13 has imprinted or otherwise affixed thereon a legend designating a particular article of stock in trade, account 70 of which is to be kept. This hand plate is carried by a lever 14 which is pivoted at 15 so that a depression of the hand plate results 75 in a rocking movement of the lever. The movement is limited by an adjustable set screw 16. The inner extremity of the lever carries a dog 17 which is pressed against a primary counter wheel 18 by a spring 19. 80 The counter wheel has numerals running from "0" to "9", there being a tooth 20 at each of the numerals, the purpose being that the dog 17 shall move the wheel 18 the distance of a tooth at a time. The numerals 85 are arranged so that successive depressions of the hand plate 13 shall show one less by the numerals at each time.

At the beginning of each tenth turn of the wheel 18 a dog 21 carried by that wheel will 90 cause a turn of the secondary counter wheel 22, which like the wheel 18, is equipped with notches or teeth 23 which the dog 21 engages. According to the illustration (Fig. 5) the numerals on the secondary counter wheel 22 95 run from "10" to "100", but in practice the numerals may run as high as may be desired. A spring 24 keeps the dog 21 in engagement with the wheel 22. The dog is pivotally mounted at 25 upon the wheel 18, the sup- 100

porting bracket 26 being sufficiently high to permit passage of the dog 21 when it passes under. It is observed that the notches 20 and 23 are of such design that liberal space is left therebetween for the application of the required numerals.

Upon depression of the hand plate 13 a tag 27 is made to appear at the window 28 (Fig. 1) of the cover 29. This tag bears a legend 10 like the one on the hand plate 13, and is intended merely to verify the immediate transaction. Full depression of the hand plate 13 causes rocking of a bell-crank 30 (Fig. 5) by virtue of the engagement of the lever 14 with 15 a lateral pin 31 on an arm of the bell crank.

Rocking of the bell-crank produces a pull upon the link 32 and a rocking of the bell-crank 33 so that as a result the tag 27 is projected upwardly in its guide 34.

Referring particularly to the cover 29, it is observed in Figure 1 it is equipped with numerous windows 35 and 36. These, in the case of the registering units 12 are intended to reveal the numerals on the counter wheels 18 and 22. Further registering units of the device have similarly designated windows 35 and 36, and the reader will understand that the purpose of these windows is the same as the purpose mentioned in respect to 30 the other windows when described.

The section 3 has hand plates 37, 38 and 39 for the purpose of registering cent, quarter and dollar sales. The hand plate 37 actuates a counter wheel 40 which has numerals running from "0" to "4". There is a counter-wheel 41 with numerals running from "0" to 35 "20" in multiples of 5. The hand plate 38 actuates a counterwheel 42 which has numerals running from "0" to "75" in multiples of 40 25, and has a complementary counter-wheel 43 provided with numerals designating 1.00, 2.00, etc. to 19.00. There is a third numeral wheel 44 with numerals designating 20.00, 40.00, 60.00 etc.

It is to be noted that a certain number of turns of the counter-wheel 40 by means of the hand plate 37 will cause a transfer of motion to the counter-wheel 41 so that that wheel partakes of a turn. It is equally true 45 that a certain number of turns of the wheel 42 by means of the hand plate 38 will produce a transfer of motion to the wheel 43 so that that wheel partakes of a turn. But not like the counter-wheel 41, the counter-wheel 50 43 has an associated hand plate 39 by means of which it can be turned directly and independently, and also unlike the counter-wheel 41 the wheel 43 has an associated counter-wheel 44. Notwithstanding the differences 55 noted the description of the unit 45, including the wheels 42, 43 and 44 will suffice for the description of the unit 46 which is similar in many respects.

Referring to the unit 45 (Fig. 6) a depression of the hand plate 38 causes rocking

of the lever 47 upon its pivot 48 so that the number wheel 42 is given a turn by means of the dog 49. The dog is held against the wheel by a spring 50. The rocking motion of the lever 47 is limited by a set screw 51. The fourth turn of the wheel 42 is accompanied by a lateral motion of the pin 52 by virtue of the engagement of a cam 53 with the ball-end 54 of the pin. The cam is carried by the wheel 42. This lateral motion of the pin 52 causes engagement of the end 55 of the pin with one of the numerous cams 56 of the number wheel 43 so that that wheel is turned to bring the numeral next in order in view of the window 35. The pin is carried by and guided in a bracket 57 against which a spring 58 acts to normally hold the ball-end against the wheel 42. The bracket provides a partial support for the shafts 59 and 60 of the two wheels, brackets 61 at the outsides of the wheels completing the support for the shafts.

Upon depression of the hand plate 39 the resulting rocking of the lever 62 causes the dog 63 to turn the number wheel 43 independently of the action of the wheel 42 and pin 52. The advantage of the arrangement is obvious: Ordinarily, a succession of 25¢ sales and depressions of the hand plate 38 will result in the registering of 1.00 sales at the wheel 43. But the occasion may arise 50 when one or more whole dollars are taken in, and in such event the salesman will depress the hand plate 39 directly so as to register such sales. A lug 64 on the number wheel 43 engages a tooth of the wheel 44 at an appropriate time thereby to cause progressive registering of said wheel, the arrangement and purpose being obvious.

Each of the counter wheels 40, 42 and 43 has an associated registering tag 65, 66 and 67 respectively bearing the legends "1¢", "25¢" and "1.00". These are made to appear at the window 28 (Fig. 1) through the engagement of the hand plate lever (for example the lever 47) with a pin 60 on a bell-crank 69. This bell-crank has a link connection 70 with a second bell-crank 71 which causes projection of the tag attached thereto.

But in the case of the number wheel 41 the associated tag 72 (which bears the legend "5¢") the bell-crank 73 is actuated by each of a plurality of pins 74 on the wheel. The rocking of the bell-crank causes a pull on the link 75, a rocking of the second bell-crank 76 and an upward motion of the tag 72 in its 110 guide 77. In respect to the number wheel 43 it is optional whether the hand plate 39 for independent operation of the numeral wheel, be applied in practice.

The operation is readily understood. The 115 relatively stationary stock section 2, so-called because of the fact that it is intended to keep account of the stock on hand, in practice has as many hand plates 13 as there are different articles in stock. Assume that there are 100 120

bags of tobacco of a certain brand in stock. The primary and secondary numeral wheels 18 and 22 will then be set as in Figure 5.

- 6 A depression of the hand plate 13 at the time of a sale of a bag of this tobacco will cause turning of both wheels 18 and 22 so that the "0" on one wheel and "100" on the other wheel will be replaced by the numeral "90" on the wheel 22 and the numeral "9" 10 on the wheel 18. The salesman may then be informed upon subsequent inspection that he has 99 bags of the particular kind of tobacco in stock.

15 The relatively movable cash section 3, so called because it is intended to keep account of the cash, has a plurality of hand plates 37, 38 and 39 with which various denominations of coin and currency can be registered. In the case of the sale of a bag of tobacco, 20 as described above, the salesman will depress the hand plate 38 thereby causing such movement of the numeral wheel 42 as will bring the numeral "25" into view at one of the windows in the cover. It is assumed 25 that the bag of tobacco cost 25¢.

In consonance with the act of depressing the hand plate 28 the section 3 rocks forwardly upon its pivot 4 (Fig. 2) so that the cash drawer 5 slides open. This feature permits the salesman to readily make change, if such is required.

30 Registrations of the wheels 40 and 42 are finally transferred to the wheels 41 and 43, and registrations of the wheel 43 are in turn 35 transferred to the wheel 44. It has already been stated that the provision of the hand plate 39 is optional. But it is an advantage to have the hand plate 39 because by means of it, sales of large value can be made to 40 register more easily upon the wheel 43.

In view of the fact that the section 3 moves in relation to the section 2 it is obviously necessary that the cover 29 be fixed upon the section 2. The fixing of the cover is 45 accomplished in any commonly known manner, and need not be the subject of a specific illustration. It is also evident that only the various hand plates 13, 37, etc. show at the front of the cover. It is also permissible 50 that the various adjusting screws 16, etc. show so that necessary adjustments can be made without undoing the cover.

I claim:

55 1. A device of the character described comprising a rocker section, a movable drawer contained thereby, a register mounted upon the section, and manual means which is operable to simultaneously actuate the register and rock the rocker section and 60 cause the drawer to open.

65 2. A device of the character described comprising a stationary section, a rocker section containing a movable drawer, pivot means by which the rocker section is attached to the stationary section, a register

carried by the rocker section, and manual means which is operable to simultaneously actuate the register and swing the rocker section upon said pivot means causing the drawer to fly open.
